UNITED STATES PATENT OFFICE.

OSKAR GRAUHERING, OF ESSEN-RÜTTENSCHIED, GERMANY, ASSIGNOR TO FRIED. KRUPP AKTIENGESELLSCHAFT, OF ESSEN-ON-THE-RUHR, GERMANY.

SIGHTING APPARATUS FOR GUNS.

No. 891,836.

Specification of Letters Patent. Patented June 30, 1908.

Application filed January 22, 1907. Serial No. 353,547.

To all whom it may concern:

Be it known that I, OSKAR GRAUHERING, a subject of the Emperor of Germany, and a resident of Essen-Rüttenscheid, Germany, 5 have invented certain new and useful Improvements in Sighting Apparatus for Guns, of which the following is a specification.

The present invention relates to a sighting apparatus for guns and it has for an object 10 to provide an apparatus which is of very compact and simple construction and which is primarily intended to be used when the ordinary sighting apparatus (attachment or the like) of the gun is put out of operation.

15 One embodiment of the sighting apparatus is shown in the accompanying drawings, by way of example.

Figure 1 is a side view of the sighting apparatus in connection with a gun-barrel, the 20 central part of the gun-barrel being broken away; Fig. 2 is a rear view; Fig. 3 is a top view; Fig. 4 is a side view of the sighting apparatus on an enlarged scale and partly in section on line 4—4, Fig. 3; Fig. 5 is a 25 side view of the sighting apparatus on an enlarged scale and partly in section on line 5—5, Fig. 3; and Fig. 6 is a section on line 6—6, Fig. 5, looking from the left and at right angles to the section plane.

30 The sighting apparatus is provided with a body A A' A² made from one piece of material and of approximate L-shape (see in particular Fig. 3). This body is provided with a dovetailed foot a³ which serves the purpose 35 of securing the sighting apparatus on the breech B of the gun-barrel. To that end, the breech is provided with a reinforcement b' having a groove b² (Fig. 2) fitting the foot a³.

40 The arms A A' of the body of the sighting apparatus form the guide for a sight-device or sight-slide C which is laterally adjustable in the known manner. The front sight D which coöperates with the rear sight c' of the sight slide is secured on the gun-barrel.

45 The shank A² of the body of the sighting apparatus is provided with an arcuate guide a⁴ for the level-carrier E, in which is journaled a worm F (Figs. 4 and 6) which meshes with teeth a⁵ provided on the shank A². The 50 level G (Figs. 3 and 5) rests in a housing G'

which is swingingly arranged on a horizontal bolt e² in a lateral projection E' of the level carrier. The housing G' can be adjusted by means of a worm H (Figs. 5 and 6) journaled in the projection E' of the level carrier E. 55

On the level carrier E is provided a mark J and on the shank A² is a corresponding elevation scale K (see in particular Fig. 5). A second mark L (Fig. 3) on the level carrier E and a scale M on the front face of the hand-wheel H' of the worm H indicate the angular position of the level G relatively to the carrier E. The shank A² in connection with the parts arranged thereon thus forms a so-called pointing arc. 60 65

When the above-described sighting device is used, the sight-slide C is first given the adjustment corresponding to the lateral deflection of the projectile for the distance of the target, and the gun-barrel is thereupon 70 directed in such a manner that the sighting line points at the target. By means of the worm H, the level G is then brought into a position in which the mark L registers with the division line of the scale M which corresponds to the terrain angle of the target, the terrain angle being measured by means of the attachment of another gun of the battery or by means of the telescope of the battery. After the terrain angle in this manner 75 has been eliminated, the level carrier E is adjusted by means of the worm F until the mark J registers with the line of the scale K which corresponds to the elevation to be imparted to the gun-barrel. Finally, the gun-barrel is given such a position by means of the elevating mechanism that the level is 80 balanced. The gun-barrel has then the required lateral direction and elevation. 85

Without departing from the scope of my 90 invention, I might do away with the front sight D and use, instead of the sight-slide C, a laterally adjustable sighting device (telescope or the like) which in itself fixes the sighting line. In such case it would be necessary to curve the guide for the sighting device formed by the arms A A'. 95

Having thus described my invention, what I claim and desire to secure by Letters Patent is: 100

- A sighting apparatus for guns, comprising
a toothed shank provided with an adjustable
sighting device; a level-carrier slidably
mounted upon said shank and provided with
5 a worm adapted to engage the toothed shank;
and a level pivotally mounted upon the level-
carrier and provided with means for adjust-
ing it relatively to said level-carrier.

The foregoing specification signed at Dus-
seldorf, Germany, this second day of Janu- 10
ary, 1907.

OSKAR GRAUHERING.

In presence of—

ALFRED POHLMÉYÉR,
M. ENGELS.
